UNITED STATES PATENT OFFICE.

FRANK E. HINNERS, OF MILWAUKEE, WISCONSIN,

CONVERTER-LINING.

1,272,442.

Specification of Letters Patent. Patented July 16, 1918.

Application filed October 19, 1917. Serial No. 197,411.

To all whom it may concern:

Be it known that I, FRANK E. HINNERS, a citizen of the United States, residing at Milwaukee, in the county of Milwaukee and State of Wisconsin, have invented certain new and useful Improvements in Converter-Linings, of which the following is a specification, reference being had to the accompanying drawing, forming a part thereof.

This invention relates to converter linings and the object of the invention is to improve the construction of converter linings in the manner hereinafter described and 15 claimed.

Heretofore it has been customary to line converters with a rammed-in lining or a built-in brick lining but such constructions are disadvantageous. It takes considerable 20 time to ram in or build in a lining and such linings must be thoroughly dried in place before the converter can be used. The drying takes considerable time so such constructions necessitate the converter being 25 out of use for a comparatively long time. It is difficult to dry the lining thoroughly and uniformly and without cracking. Moreover the lining chips off and makes "cold heats" and there is considerable expense 30 when a converter loses a heat.

According to my invention the lining is formed and dried outside of the converter with the result that a better lining is secured and the converter can be used practically continuously. When a new lining is 35 required, it is only necessary to dump the old lining, insert a new lining and proceed with a heat.

Referring to the drawings which accompany 40 this specification and form a part hereof, which drawings illustrate an embodiment of this invention, and on which drawings the same reference characters are used to designate the same parts wherever 45 they may appear in each of the several views, Figure 1 is a vertical section of a side-blown converter; Fig. 2 is a plan view of a section of lining containing the twyer holes; and Fig. 3 is an elevation of a part 50 of the converter.

Referring to the drawings, the shell of the converter is illustrated as composed of a removable top 1, a cylindrical body 2 and a bottom 3. The top 1 is provided with 55 a flange 4 and the body 2 is provided with a flange 5. Fastening members 6 pass

through holes in these flanges to removably secure the top 1 to the body 2. These fastening members are illustrated as bolts provided with heads and slots. Wedges 7, 60 driven into the slots, firmly clamp the top 1 to the body 2. The reference numeral 8 designates the wind box from which the air enters the converter through twyer holes 9.

I prefer to form the lining for the body 65 of the converter in sections of a general ring form. By forming the lining in sections, the sections can be more easily formed and handled and can be more easily and more thoroughly dried. In the construction illustrated by the drawings, three sections 10, 11 and 12 are shown. The lining, or sections, is made enough smaller than the body 2 so that a packing 13 can be rammed between the lining and the body 2. 75

The lowermost section 10 is illustrated as provided with twyer holes 14 and as having its lower part shaped to fit against the inclined part of the bottom 3. The bottom lining 15 may be composed of sand or 80 ganister filled in the bottom of the converter before the lining of the body is set in and the top lining 16 may be composed of brick or ganister. The sections 10, 11 and 12 of the lining may be formed from brick or 85 other suitable material. I prefer to form them from ganister, ground quartz, silica clay mixed up with water and a little molasses. The sections are rammed up in molds and may be reinforced by rods 17 90 and hooks 18 or in any suitable manner. At the tops of the sections cavities are left to expose hooks so that the sections can be readily handled by slings. After the sections have been formed, they are thoroughly 95 dried in a core-oven or in any suitable manner and after they are dried they are ready for use at any time. The bottom lining 15 and the top lining 16 may be formed in the same manner. 100

When the lining is to be assembled with the shell of the converter, the bottom lining 15 and the top lining 16 are placed. The lowermost section 10 is placed in position, the cavities 19 are filled up with wet clay or 105 ganister and wet clay or ganister is rammed between the lining and the body 2 to form the packing 13. Twyer holes 20 are formed through the packing 13 in line with the twyer holes 9 and 14. The twyer holes 20 110 through the packing 13 may be formed in any suitable manner. The cover of the wind

box 8 is removable and a bar can be driven through the packing 13. The packing 13 can be rammed between the lowermost section 10 and the shell of the converter until the twyer holes are reached. A plug can then be placed in a twyer hole 9 and extending into a twyer hole 14 and the packing 13 can be rammed around the plugs, a plug being provided for each twyer hole, and the 10 plugs can afterward be withdrawn. The top of section 10 is then smeared with wet clay or ganister, the section 11 is then placed in position and the cavities 19 filled up and the packing 13 rammed around it. 15 The section 12 is placed in the like manner and the top is then secured to the converter. A smear of wet clay or ganister is used to close the joints between the section 12 and the top lining 16 and between the section 10 and the bottom lining 15. As soon as the 20 lining is in place the converter is ready for use as the lining is already baked and dry and the smears in the joints do not contain enough water to do any harm and dry 25 quickly. The packing 13 and the filling in the cavities 19 will dry and the steam or vapor therefrom will escape through the holes in the body 2.

The two great advantages of my lining 30 over the prior linings are the great lessening of the time that the converter must be out of commission while being relined and the longer life of a lining which is molded and baked or dried outside of the converter. In 35 using the old linings I have been able to obtain from seven to twenty heats from a single lining. With my new lining I have obtained an average of about thirty-two heats from a single lining and have had forty 40 heats without relining.

The converter illustrated by the drawings is a type of converter used in a steel foundry to make steel for steel castings, but my invention is not limited to such use nor to the 45 specific form of side-blown converter illustrated. It will be understood, of course,

that in using the converter for making steel, iron is melted and the molten metal is introduced into the converter to be purified and converted into steel in the ordinary or 50 any preferred manner. My invention relates to lining the converters and not to the specific construction or use of converters.

What is claimed is:

1. A converter lining formed as a unit to 55 the shape of the converter shell with a space therein adapted to receive molten metal and baked or dried outside of the shell of the converter.

2. A converter lining formed of sections 60 each of the sections being formed as a unit to the shape of the converter shell with a space therein adapted to receive molten metal and baked or dried outside of the shell of the 65 converter.

3. A converter lining formed in ring-like sections which have been formed and baked or dried outside of the shell of the converter and which are assembled in the shell of the converter with a wet packing 70 between the sections and the shell of the converter so that molten metal can be poured into the converter notwithstanding the presence of the wet packing.

4. In a converter, the combination with a 75 converter shell provided with holes of a converter lining formed to shape and baked or dried outside of the shell of the converter, and a packing interposed between the shell and the lining.

5. The method of lining converters which consists in forming the linings to shape and baking or drying them outside of the converter shells, inserting the linings in the shells with a wet packing between a lining 85 and a shell, and permitting the wet packing to dry from the heat of the charge of molten metal in the converter.

In witness whereof I hereto affix my signature.

FRANK E. WINNERS.
